UNITED STATES PATENT OFFICE.

GEORGE H. GIBSON, OF MONTCLAIR, NEW JERSEY.

FURNACE REGULATION.

Application filed May 25, 1918. Serial No. 236,450.

To all whom it may concern:

Be it known that I, GEORGE H. GIBSON, a citizen of the United States of America, and a resident of Montclair, in the county 5 of Essex, State of New Jersey, have invented a certain new and useful Improvement on Furnace Regulation, of which the following is a true and exact description, reference being had to the accompanying 10 drawings, which form a part thereof.

My present invention comprises improved means for controlling combustion in furnaces such as steam generating boiler furnaces, and the primary object of the invention is 15 to provide effective means for automatically proportioning the amounts of primary air supplied to such a furnace and supporting combustion therein, and to combine therewith provisions for maintaining a predetermined pressure in a combustion chamber of the furnace. Other and more specific objects of the invention are to provide improved regulating means for, but not necessarily limited to use in effecting the first 20 stated object of the invention, and to provide novel means for supplying the secondary air above the fuel bed of the furnace.

The various features of novelty which characterize my invention are pointed out 25 with particularity in the claims annexed to and forming a part of this specification. For a better understanding of the invention, however, and its advantages reference should be had to the accompanying drawings and 30 descriptive matter in which I have illustrated and described preferred embodiments of my invention.

Of the drawings:

Figure 1 is a somewhat diagrammatic 40 representation, with parts broken away and in section, of a steam generating boiler furnace and combustion control apparatus associated therewith.

Figure 2 is a partial section taken on the 45 line 2—2 of Figure 1.

Figure 3 is a partial section taken on the line 3—3 of Figure 1.

Figure 4 is a diagrammatic representation, with parts broken away and in section, 50 of a steam generating boiler furnace provided with a modified form of regulating apparatus.

Figure 5 is a partial section on the line 55 5—5 of Figure 4.

Figure 6 is a view of the same general

character as Figure 1, illustrating a third form of regulating apparatus.

Figure 7 is a diagrammatic elevation, with parts broken away and in section, of a heating furnace of the type employed in 60 heating houses with a form of combustion regulating mechanism suitable for use therewith.

In the drawings, and referring first to the construction shown in Figs. 1, 2 and 3, A 65 represents a conventionally illustrated steam generating boiler furnace of the return tubular type, in which A' is the ash pit, A², the portion of the combustion chamber above the fuel bed separating this chamber from 70 the ash pit beneath it, and A³, the portion of the combustion chamber lying beyond the bridge wall B. The throat or passageway above the bridge wall connecting the combustion chambers A² and A³ is divided up 75 into a plurality of tortuous passages by vertical posts C' and C² of refractory material, shown in the form of posts or columns arranged in two staggered rows. The secondary air for burning the combustible gases 80 rising from the fuel bed, is supplied to the furnace through a conduit or channel B' in the bridge wall. This conduit, which may be open at the ends to the atmosphere, discharges air into the throat connecting chambers A² and A³, through a plurality of discharge ports or tuyères B². As shown, each port B² opens at its upper end immediately 85 back of a corresponding post C'. The primary air for combustion is supplied to the ash pit A' through the discharge conduit D' of a fan or blower D, operated by a steam motor D². The latter is supplied with the necessary steam motive fluid through a 90 branch pipe D³ connected to the steam pipe E of the boiler. The supply of steam through the pipe D³ to the motor D is controlled by a throttle valve F, having its operating stem connected to the diaphragm of a fluid pressure device G. This diaphragm has one 95 side exposed to the pressure of the atmosphere and the other side exposed to the steam pressure transmitted from the steam pipe E through the branch pipe G'. The device G, shown in Fig. 1, is identical in 100 construction with the device G shown in section in Fig. 6. The purpose of the device G, and the valve F controlled by it, is to so vary the amount of primary air supplied to 105 the furnace as to maintain a constant steam

110

pressure in the boiler. The stack draft to which the furnace is subjected is controlled by a damper H, located in the stack connection A⁴ of the furnace, and adjusted by the reversible electric motor I. The latter is connected to electric supply conductors 1 and 2 to cause the motor to run in one direction or the other, or is disconnected from said conductors by an automatic switch mechanism collectively indicated by the symbol J. This switch mechanism comprises a pivoted switch arm J' carrying contacts bridging stationary contacts J² and J³ when the switch arm J' is swung in one direction from a neutral position, and bridging contacts J² and J³ when the switch arm J' is swung in the opposite direction from the neutral position shown in Fig. 1. When the conduits J² and J³ are bridged by the switch arm J' the motor I is caused to run in the direction to decrease the throttling effect of the damper H. In the neutral position of the lever J', shown in Fig. 1, the motor I does not run in either direction, and thereby maintains the stack damper H in whatever adjustment it may then be in.

The switch arm J' is carried by a pivoted balance member K supported by a knife edge pivot K'. The balance K comprises oppositely extending horizontal arms on which are hung receptacles L, M, N and O. As shown, the receptacle L is suspended from the outer end of one of the horizontal arms of the balance K, and the receptacle O is suspended from the outer end of the other horizontal arm. The receptacle M is suspended from the same arm as the receptacle L at an adjustable distance between the receptacle L and the pivot K, and the receptacle N is suspended from the other horizontal arm at an adjustable distance between the receptacle O and the pivot K'. The upper end of the receptacle L is connected by a flexible conduit P' to a straight portion of the primary air supply conduit D', and in such manner as to transmit the static pressure in the conduit D' to the upper end of the receptacle L. A Pitot tube Q in the conduit D' is connected by a flexible conduit P² to the upper end of the receptacle O. The lower ends of the receptacles O and L are connected by a flexible conduit P³. The receptacles O and L and the conduit P³ are partially filled with a suitable sealing liquid which may be water or oil, and which is caused to flow from the receptacle O into the receptacle L or back, accordingly as the flow of air through the conduit D' increases and decreases. The upper end of the receptacle N is connected by the flexible pressure transmitting pipe P⁴ to the combustion space of the furnace. As shown, the pipe P⁴ leads from the throat connecting the combustion chambers A² and A³. The lower ends of the receptacles M

and N are connected by a flexible conduit P⁵, and these receptacles are partially filled with a suitable sealing liquid which may be the same as the sealing liquid partially filling the receptacles L and O. The upper end of the receptacle M' is open to the atmosphere at M'. A central depending arm from the balance member K supports an adjustable balance weight K². Normally this weight K² is so adjusted that the balance member K is in neutral equilibrium when the liquid level in the receptacles L and O are the same, and the liquid levels in the receptacles N and M are the same, so that any displacement of liquid from one receptacle to another tends to produce a corresponding turning movement of the balance member K about its pivotal axis.

With the apparatus described the passage of air into the ash pit, through the conduit D', results in a pressure at the inlet to the Pitot Q, and hence in the air space above the liquid in the receptacle O, which is greater than the static pressure in the conduit D', transmitted to the air space above the liquid in the receptacle L. In consequence the flow of air through the conduit D' causes a displacement of liquid from the receptacle O into the receptacle L, which is a function of the rate of flow through the conduit D'. According to well-known laws of fluid flow the displacement of liquid thus produced, will be approximately proportional to the square of the volume of flow through the conduit D'. Similarly, the displacement of liquid from the receptacle M into the receptacle N will be proportional to the amount by which the pressure of the atmosphere exceeds the pressure in the throat or passageway connecting the combustion chambers A² and A³. This pressure differential creates, and is a measure of the flow of secondary air into the furnace through the ports B². Since the ports B² form fixed discharge orifices, the amount of air passing through them into the furnace will be approximately proportional to the square root of said differential between the pressure of the atmosphere and the pressure in the throat or passageway connecting the chambers A² and A³.

Since the displacement of liquid from the receptacle O into the receptacle L tends to turn the balance member K in a clockwise direction, while the displacement of liquid from the receptacle M into the receptacle N tends to turn the balance in the opposite direction it will be apparent that the initial balance of the member K will be maintained only in case the leverage, due to excess weight of liquid in the receptacle L, is balanced by the turning moment in the opposite direction due to the excess liquid in the receptacle N. It follows, in consequence, that unless a given increase or de-

crease in flow through the conduit D' is accompanied by a predetermined increase or decrease in the amount of secondary air discharged through the ports B², the balance

- 5 K will be shifted in one direction or the other so as to bridge the contacts J² and J³ or j² and j³, and thus cause the motor I to adjust the damper H so as to increase or decrease its throttling effect and thereby maintain the predetermined ratio between the amounts of primary and secondary air supplied to the furnace.

Furthermore, the balance K operates to maintain a minus pressure in the combustion chamber which is very small, since but a relatively minute differential between the pressure of the atmosphere and the pressure in the combustion chamber is necessary to obtain the maximum desired flow of secondary air into the combustion chamber. Strictly speaking, the operation of the apparatus effects and depends upon a variation in the combustion chamber pressure, which increases and decreases as the boiler steam pressure falls and rises; but this variation is so slight that the device operates practically to maintain a constant combustion chamber pressure or balanced draft. It will be observed that the balance K adjusts the stack damper H in response to changes in the resultant of two opposing control forces. One of these control forces, namely: the pressure differential transmitted to the balance through the pipes P' and P², is a measure of the rate of primary air flow through the conduit D', and increases and decreases as the boiler steam pressure falls and rises, and hence is a function of the boiler steam load or boiler furnace heat requirements. The second control force, namely: the pressure differential transmitted to the balance through the inlet M' and pipe P⁴, is a function of the pressure in the combustion chamber of the furnace. Since the total flow of heating gases through the boiler furnace is kept proportional to the rate of primary air flow through the conduit D', and said primary air flow is controlled by the device G, the latter forms a means for making the total flow of heating gases through the boiler furnace dependent upon the steam pressure, while the balance K acts directly on the stack damper adjusting motor I to make the pressure in the combustion chamber of the boiler vary with the rate of flow of heating gases through the furnace. The refractory posts C and C', in conjunction with the arrangement of secondary air supply ports B², insure a very intimate and effective mixture of the combustible gases passing out of the combustion chamber A² with the secondary air and thus insure a highly efficient combustion. The sensitivity of the balance, and the ratio of pressures maintained by it, may be varied by ad-

justing the receptacle M and N toward and away from the pivot K', and by raising and lowering the weight K².

In the form of my invention illustrated in Fig. 4 the furnace proper, and the means for supplying primary air thereto in regulated amounts, are shown as identical with the apparatus disclosed in Fig. 1, except that the secondary air is passed into the horizontal channel B' in the bridge wall BA, through a conduit B³. The stack damper HA in Fig. 4 is connected to a piston R' working in a fluid pressure motor cylinder R. The latter has its opposite ends connected by pressure transmitting pipes P⁵ and P⁶ to the cylinder S of a controlling valve. The valve member S', working in the cylinder S, as shown, is balanced and is connected by an arm T² to the diaphragm T' of a pressure motor T, the chamber in which is connected to the interior of the combustion chamber by a pressure pipe P⁷. As shown, the pressure pipe P⁷ opens to the combustion space of the furnace in the passage connecting the chambers A² and A³. A pressure motive fluid, as compressed air, is supplied to the cylinder S through the supply conduit S³. The arm T² passes through a slot S² in the side wall of the cylinder S, serving not only as a passage for the arm T², but also as an exhaust port. An adjustable loading spring T³ is connected to the arm T², so as to impart a slight pull to the left on the diaphragm T'. In consequence the pressure in the chamber of the motor T will normally be slightly below that of the atmosphere. The valve member S' proper is so formed that when the pressure in the pressure chamber of the motor T falls below the desired pressure and the diaphragm T', through the arm T², thereupon moves the piston S' to the right from the position shown in Fig. 4, the pressure fluid supplied by the pipe S³ will pass through the pipe P⁶ into the left hand end of the cylinder R, while at the same time the right hand end of the cylinder R will be connected through the pipe P⁵, and the peripheral channel in the valve member S' to the exhaust port S². This will move the piston R' to the right and thereby throttle the stack draft and increase the pressure in the combustion chamber. Similarly, when the pressure in the combustion chamber rises above the desired value the diaphragm T' will displace the valve member S' to the left, thereby connecting the right hand end of the cylinder R to the cylinder S, and the left hand end of the cylinder R to exhaust. This will cause the damper HA to open and thereby restore the desired pressure in the combustion chamber.

In this form of my invention the passage of secondary air into the channel B', through the passage B³, is regulated by a sliding

throttle valve U^2 connected to a piston U' , working in a cylinder U . The right hand end of the cylinder U is connected by a pressure pipe P^8 to a Pitot Q' located in the 5 primary air supply conduit D' , and the static pressure in the conduit D' is transmitted to the left hand end of the cylinder U by the pipe P^9 . A spring U^3 exerts a slight loading force on the piston U' , tending 10 to move it to the right. With the arrangement described an increase or decrease in the rate of flow, through the conduit D' , produces a corresponding opening or closing movement of the valve or damper U^2 . As 15 shown, the conduit B^3 is so shaped at the level of the damper U^2 that slide movements of the damper will produce greater differences in throttling effect when the volume of flow through the conduit D' is small than 20 when large. Preferably, as shown, the cross section of the conduit B^3 is such that the free area past the damper U^2 in the conduit B^3 will be proportional to the square root of the difference between the pressures transmitted 25 to the two ends of the cylinder U .

With the apparatus shown in Fig. 4, the amount of primary air supplied is dependent upon the steam pressure, and the pressure in the combustion chamber of the furnace will be maintained constant and slightly below that of the atmosphere, while the amount of secondary air supplied will depend upon the free area of flow through the conduit B^3 past the damper U^2 , and this area will be proportional to the volume of flow through the conduit D' , so that in this form of my invention, as in the first described, the ratio of primary and secondary air supplied is kept constant, while at the same time, the pressure in the combustion chamber is also maintained constant. Certain novel features of construction and arrangement of the apparatus shown in Fig. 4 not claimed herein, are claimed in my divisional application Serial No. 38,446, filed June 20, 1925.

The furnace in the construction shown in Fig. 6 is shown as essentially the same as that first described, except that the secondary air is admitted at the front as well as the rear of the fuel bed and in close proximity to the latter. At the rear of the fuel bed secondary air is supplied from a horizontal channel B^{10} , which may have its ends open to the atmosphere, and which discharges air into the combustion chamber through ports B^{11} , which open to the chamber A^2 , through the inclined face B^{12} of the bridge wall. Secondary air is supplied at the front of the fuel bed through ports B^{16} opening through the inclined front wall of a horizontal air supply conduit B^{15} , which may also have its ends open to the atmosphere. This arrangement for introducing secondary air insures an intimate mixture of

the secondary air with the gaseous products arising from the fuel at points in close proximity to the fuel bed. This method of introducing secondary air is especially advantageous when the fuel burned is bituminous coal giving off volatile gases and vapors, which quickly decompose and which it is advantageous to burn before decomposition can occur.

The stack draft damper HB in the stack draft connection A^4 of the furnace AA is controlled by a fluid pressure motor G , having its pressure chamber connected by the pipe G' to the steam pipe E , the arrangement being such that the damper HB opens and closes as the steam pressure falls and rises. The primary air passing to the ash pit A' of the furnace AA , through the conduit D' from the blower D , is controlled by a device jointly responsive to the pressure in the chamber A^2 , and to the quantity of flow through the conduit D' . For this purpose I employ a balance W , which has an adjustable pivot, and has an adjustable arm W^2 connected to the operating arm of a valve FA in the pipe D^3 supplying steam from the pipe E to the blower motor D^2 . One end of the balance W has suspended from it a bell X , and the other end of the balance has suspended from it a bell X' . Both of the bells X and X' have their lower edges dipping into a body of sealing liquid contained in a receptacle X^2 . The upper end of the bell X is exposed to the pressure of the atmosphere, but the upper end of the bell X' is protected from the direct pressure of the atmosphere by locating it in an enclosure forming a portion of the receptacle X^2 . The pressure in the furnace chamber A^2 is transmitted to the interior of the bell X through the pipe P^{12} . The static pressure in the conduit D' is transmitted to the interior of the bell X' through the pipe P^{11} . The pressure of the Pitot tube Q^2 , extending into the channel D' is transmitted to the top of the chamber X^3 in which the bell X' works. To avoid stuffing box difficulties the bell X' is formed with a central tubular portion depending from the top of the bell at the margin of an aperture in the latter and extending into the liquid bath in the receptacle X^2 . Telescoping with the tubular portion X^4 is a tubular part carried by the top wall of the chamber X^3 , which dips into the liquid in the lower portion of the tubular portion X^4 . The link connecting the bell X' to the balance W passes loosely through the tubular part X^5 .

With the construction described the total volume of draft passing through the combustion chamber of the furnace will depend upon the steam pressure and will be automatically varied by the device G in such manner as to tend to maintain a constant steam pressure. At the same time the bal-

ance W will adjust the valve FA as required to maintain a constant ratio between the amounts of primary and secondary air supplied to the combustion chamber, and so as to maintain the pressure in the combustion chamber of the furnace practically constant, since the variation in this pressure necessary to control the admission of secondary air is so slight, as I have already explained, as to be practically negligible.

In Fig. 7 I have illustrated the use of my invention in connection with a heater AB, suitable for use in house heating, and which may be either a hot air, hot water or vapor heater. In this heater the rate of combustion is controlled by opening and closing a damper HC, to thereby admit more or less atmospheric air into the chimney stack connection A¹, and correspondingly decrease or increase the effective draft to which the furnace is subjected. D⁵ represents an air inlet to the furnace opening into the ash pit of the furnace A⁵, and D⁶ represents a secondary air supply conduit opening to the furnace chamber A⁶ above the fuel bed. These inlets are open at their outer ends to the atmosphere. The ratio of primary and secondary air is controlled in this case by a damper HD in the secondary air supply conduit D⁶. This damper is connected by a chain Z⁴ to the gear wheel Z³, which may be driven in one direction or another through a worm shaft Z² by a suitable motor Z⁵, which may be a spring motor. When the gear wheel Z³ turns in the clockwise direction, the pull of the chain Z⁴ moves the valve HD in one direction, and when the wheel Z³ is rotated in the counter-clockwise direction the valve HD is correspondingly adjusted by means of the weight Z⁵⁰ connected to the lower end of the chain Z⁴ and holding the latter taut. As shown, the motor is provided with two driving gears Z⁷ and Z⁸, which are connected by the bevel gear Z⁹ and turn in opposite directions. A gear wheel Y⁸ splined on the worm shaft Z² can be moved into mesh with either of the gears Z⁷ or Z⁸ from the neutral position shown in the drawing in which it is out of mesh with each of these gears. The motor Z⁵ may be started and stopped by moving a stop arm Y⁷ out of and into engagement with the escapement device Z⁶ of the motor. The gear wheel Y⁸ is shifted on the worm shaft Z² and the arm Y⁷ moved into and out of engagement with the escapement device Z⁶ by a rod Y⁶ connected to the arm Y⁴ of a balance lever Y² fulcrumed at Y⁸. The arm Y⁷ is connected to the rod Y⁶, and with the latter is formed with a hook at its end remote from the balance Y², which enters a groove in the hub of the gear Y⁸. The balance lever member Y² has two oppositely extending horizontal arms, from each of which is adjustably suspended a bell Y. The

two bells Y dip into a bath of sealing liquid contained in a receptacle Y' open at its upper end. The static pressure in a restricted portion of the primary air supply conduit D⁵, at which the static pressure is less than the total pressure, is transmitted to the interior of one of the bells Y by a pipe P¹⁴, and the static pressure in the secondary air supply conduit D⁶ is transmitted to the interior of the other bell Y through a pipe P¹⁵.

To magnify the difference between the total pressure and the static pressure at the point in each air supply conduit, connected to the interior of the corresponding bell Y, I shape the outer end of each of the air supply conduits D⁵ and D⁶ into the form of a Venturi section, and mount in each of these Venturi sections a small Venturi tube D¹⁰ having its discharge end located at the throat of the large venturi in which it is mounted, I connect the pipes P¹⁴ and P¹⁵ to the throats of the corresponding small venturis.

With the construction shown in Fig. 7, the balance lever Y² will turn in a clockwise direction, or in the contrary direction, accordingly as the ratio of primary to secondary air supplied to the furnace decreases or increases from a predetermined ratio. When the balance lever Y² turns in the clockwise direction the gear wheel Y⁸ is moved into mesh with the motor gear Z⁸, and the gear wheel Z³ is then rotated in the direction to close the damper HD and thereby increase the ratio of primary air to secondary air supplied to the furnace. When the balance lever Y² swings in the opposite direction from the neutral position shown in Fig. 7 the gear Y⁸ is moved into mesh with the gear wheels Z⁷, and at the same time the stop arm Y⁷ is moved out of engagement with the escapement device Z⁶, thus permitting the motor to rotate the wheel Z³ in the direction to open the damper HD, and thereby decrease the ratio of primary to secondary air. The ratio of primary to secondary air may be adjusted by adjusting the bells Y³ toward and away from the pivot axis Y' of the balance Y². The adjustable weight Y⁶ forms a means for calibrating the apparatus so that the balance will be in a condition of neutral equilibrium when the pressure differential effect thereon is zero.

While in accordance with the provisions of the statutes I have illustrated the best form of my invention now known to me, those skilled in the art will understand that changes may be made in the form of the apparatus disclosed without departing from the spirit of my invention as set forth in the appended claims, and that some features of my invention may sometimes be used to advantage without a corresponding use of other features of the invention.

Having now described my invention, what

I claim as new and desire to secure by Letters Patent, is:

1. The combination with a furnace having a combustion chamber and primary and secondary air supplies, of means responsive to the amounts of primary air and secondary air supplied and to the pressure in the combustion chamber of the furnace and means controlled by the first mentioned means for maintaining a predetermined ratio between the amounts of primary and secondary air supplied and regulating the pressure in the combustion chamber of the furnace.
2. The combination with a furnace having a combustion chamber and primary and secondary air supplies, of means responsive to the amounts of primary air and secondary air supplied and to the pressure in the combustion chamber of the furnace and means controlled by the first mentioned means for maintaining a predetermined ratio between the amounts of primary and secondary air supplied and for maintaining a practically constant pressure in the combustion chamber of the furnace.
3. The combination with a furnace having a grate for solid fuel and a combustion chamber at one side of the grate, a secondary air inlet to said combustion chamber and a primary air inlet to the furnace at the opposite side of the grate, of controlling means responsive to the pressure in the combustion chamber and to the amount of primary air supplied and means controlled by the first mentioned means for regulating the pressure in the combustion chamber and maintaining a predetermined ratio between the amounts of primary and secondary air supplied.
4. The combination with a furnace having a grate for solid fuel and a combustion chamber at one side of the grate, an inlet for atmospheric air opening to said combustion chamber, a forced air supply to the furnace at the opposite side of the grate from said combustion chamber, and means responsive to the pressure in the combustion chamber and to the amount of primary air passing to the furnace and means controlled by the first mentioned means for regulating the pressure in the combustion chamber and maintaining a predetermined ratio between the amounts of primary and secondary air supplied.
5. The combination with a furnace having primary and secondary air supplies, of a device for adjusting one of said supplies, and controlling means therefor, comprising a compound differential pressure gauge and means for subjecting said gauge to a differential pressure which is a function of the amount of primary air supplied and to an opposing differential pressure which is a function of the amount of secondary air supplied.
6. The combination with a furnace having primary and secondary air supplies, of a device for adjusting one of said supplies, and controlling means therefor comprising a tilting differential pressure gauge of the sealing liquid displacement type, and means for effecting a displacement of the gauge sealing liquid which is a measure of the amount of primary air supplied, and simultaneously effecting and opposing liquid displacement which is a measure of the secondary air supplied.
7. The combination with a furnace having separate primary and secondary air inlets, of means responsive to the differential between the pressure of the atmosphere and the pressure in the furnace, means responsive to the amount of air entering the furnace through the primary air inlet and means jointly controlled by the two means first mentioned for maintaining a predetermined ratio between the primary and secondary air entering the furnace and for regulating said pressure differential.
8. The combination with a furnace having a combustion chamber and a secondary inlet to said chamber from the atmosphere of fixed resistance, and having a separate primary air inlet, of means jointly responsive to the amount of air passing into the furnace through the last mentioned inlet and to the difference between the pressure of the atmosphere and the pressure in the combustion chamber and means controlled by the first mentioned means for maintaining a predetermined ratio between said difference in pressure and the air passing through said inlet.
9. In a boiler furnace combustion regulating system, the combination of means for maintaining a control force which increases and decreases with the boiler load requirements, means for creating a second control force varying the pressure in the boiler furnace combustion chamber, and a stack damper actuator jointly controlled by said forces.
10. In a boiler furnace combustion regulating system, the combination of a device responsive to the boiler steam pressure for maintaining a control force which increases and decreases as said pressure diminishes and increases, means for creating a second control force varying with the pressure in the boiler furnace combustion chamber, and a stack damper actuator subject to the differential action of said forces.
11. In a boiler furnace combustion regulating system, the combination with a device responsive to the boiler steam pressure for controlling the rate of flow of the heating gases through the furnace, of a device controlling the boiler furnace combustion chamber pressure, and means for subjecting

the last mentioned devices to two control forces, one of which is dependent on the rate of flow of the heating gases through the furnace, and the other of which is proportional to the difference between said pressure and the pressure of the atmosphere.

12. In a boiler furnace combustion regulating system, the combination with means regulating the supply of air for combustion to the furnace, and means regulating the escape of products of combustion from the furnace, of a device responsive to the boiler steam pressure directly controlling one of said means, and a controlling device for the other of said means comprising a balance and means for subjecting said balance to two opposing forces, one of which is a function of the boiler steam pressure and the other of which is a function of the pressure in the combustion chamber of the furnace.

13. In a boiler furnace combustion regulating system, the combination with means regulating the supply of air for combustion to the furnace, and means regulating the escape of products of combustion from the furnace, of a device responsive to the boiler steam pressure directly controlling one of said means and control mechanism for the other of said means jointly responsive to the boiler steam pressure and to the pressure in the combustion chamber of the furnace.

14. In a combustion regulating system for a boiler furnace, the combination with means for varying the rate of supply of air for combustion in inverse response to the pressure of the steam generated, of means for regulating the furnace pressure in direct response to the differential between the fur-

nace pressure in the furnace and the pressure of the atmosphere and in inverse response to the steam pressure.

15. In a combustion regulating system for a boiler furnace, the combination with means for varying the rate of supply of air for combustion in response to boiler load, of means for regulating the furnace pressure in response both to the differential between the pressure in the furnace and the pressure of the atmosphere, and to the boiler load.

16. In a combustion regulating system for a boiler furnace, the combination with means for varying the rate of gas flow through the furnace in response to a force which is a function of the boiler load, of means tending to maintain a constant vacuum in the furnace, and means responsive to said force for modifying the action of said vacuum maintaining means to procure a predetermined increase in vacuum on a given increase in boiler load.

17. In a combustion regulating system including provisions for varying the rate of supply of air in inverse response to the pressure of the steam generated, the combination with mechanism for regulating the furnace pressure, of controlling means for said mechanism including a balance, means for subjecting said balance to a force proportional to the difference between the furnace pressure and the pressure of the atmosphere, and means for subjecting said balance to a force opposing the first mentioned force and increasing and decreasing, respectively, as the pressure of the steam generated decreases and increases.

GEORGE H. GIBSON.
